PULP THICKENING AND WASHING APPARATUS

Johan Christoffer Fredrik Carl Richter, Oslo,
Norway, assignor to Aktiebolaget Kamyr, Oslo,
Norway

Application October 8, 1937, Serial No. 168,087
In Norway October 14, 1936

1 Claim. (Cl. 210—199)

With circular screen dehydrating apparatus for fiber suspensions use is ordinarily made of a pressure roller or so-called dandy roll which is pressed against the screen cylinder and serves to dehydrate or primarily compress the layer of stuff formed on the surface of the screen cylinder. If, as known, the dandy roll is so arranged as to be partially immersed in the stuff the water expressed thereby flows back to the stuff box, particularly if the dandy roll is not constructed as a suction roller or a special part or compartment is not provided over the entire width of the stuff box through which this water can pass to the exterior.

The object of the invention is to provide a simple arrangement wherein the construction of the dandy roll as a suction roller or the provision of a special part on the stuff box is unnecessary.

According to the invention this is accomplished in that the dandy roll immersed partially in the stuff, is packed off at one or both ends, at full diameter, by the side wall or side walls of the stuff box and is passed through, for example, by the use of the well known sliding packing.

An exemplary embodiment of the invention is shown on the accompanying drawing.

Fig. 1 is a diagrammatic cross section.

Figs. 2a and 2b are diagrammatic axial sections through the screen cylinder and the dandy roll on lines A—A and B—B of Fig. 3, and

Fig. 3 is a diagrammatic plan view.

As shown on Fig. 1, the dehydrating apparatus consists in the usual manner of a stuff box 1, in which a rotating, rigidly journaled, screen-cloth covered cylinder 2, with or without a suction device, is disposed.

Mounted adjacent cylinder 2 is the movably journaled dandy roll 3 which is immersed partially in the stuff and is pressed by a spring or other equivalent device against cylinder 2.

The dandy roll 3 and the cylinder 2 are, in the manner known for screen cylinders, fitted in the side walls of the stuff box 1 by means of packings 9 disposed at the periphery. The packings 9 for the dandy roll 3 are constructed so that they permit sufficient freedom of movement for the roller 3 to exert the necessary elastic resilient pressure action. This is accomplished by providing a channel member 17 mounted upon each

end of the dandy roll for rotation therewith and providing members 18 mounted on the stuff box 1 fitting into the member 17 with a fluid-tight fit while at the same time providing sufficient clearance between the bottom of the channel members and the edges of the members 18 to permit movement of the dandy roll transverse to its longitudinal axis.

As shown by the exemplary constructions, the cylinder 2 and the roll 3 can be driven by the same shaft 4, which is connected with the cylinder 2 through a worm drive 5, while the dandy roll 3 oscillatably journaled on the arms 6 is driven through a gear drive from the gear 7, which is journaled coaxially with the rotational axis of the arms 6.

The stuff box 1 is fed in the usual manner from an inlet 8 having the usual overflow or by a pump. The water expressed from the layer of stuff 10 passes into the interior of the screen cylinder and the dandy roll and flows off at one or, as shown on Figs. 2a and 2b at both sides, while the layer of stuff is detached or loosened from the screen cylinder by a guide surface 11. A spraying tube is shown at 12 and a pressure roller at 13.

I claim:

A circular screen dehydrating apparatus for fiber suspensions such as cellulose wood cutting or the like comprising a stuff box, a screen cylinder located in said stuff box, a dandy roll mounted for movement toward and away from said screen cylinder, cooperating with said screen cylinder and partially immersed in the suspension in said stuff box, said dandy roll and screen cylinder extending through the side walls of said stuff box, packings encircling the entire outer diameters of said roll and cylinder at an end thereof, so that water passing into said dandy roll may pass freely off laterally through an open end, said packing encircling said dandy roll permitting movement of said roll transverse to the axis thereof and said packing comprising a cooperating channel member and a member extending into said channel member in liquid-tight relationship with sufficient clearance between the bottom of said channel member and the other member to permit said transverse movement of said roll.

JOHAN CHRISTOFFER
FREDRIK CARL RICHTER.
